UNITED STATES PATENT OFFICE.

MAXINE AVERILL, OF NEW YORK, N. Y.

DESIGN FOR A STUFFED TOY ANIMAL.

Application filed August 20, 1928. Serial No. 27,893. Term of patent 3½ years.

To all whom it may concern:

Be it known that I, MAXINE AVERILL, a citizen of the United States, residing at Hotel White, Lexington Avenue and 46th Street, in the borough of Manhattan, city, county and State of New York, have invented a new, original, and ornamental Design for a Stuffed Toy Animal, of which the following is a specification, reference being had to the accompanying drawing, forming a part thereof, and showing in Fig. 1 a front view and in Fig. 2 a side view of the stuffed toy animal embodying my design.

I claim:

The ornamental design for a stuffed toy animal substantially as shown.

MAXINE AVERILL.
